United States Patent

Des. 234,782
Patented Apr. 8, 1975

234,782

GOLF PUTTER

Edward Creed, 5830 Perry Lane, Merriam, Kans. 66203

Filed Aug. 8, 1973, Ser. No. 386,729

Term of patent 14 years

Int. Cl. D21—02

U.S. Cl. D34—5 GC

Fig. 1.

Fig. 2.

Fig. 3.

Fig. 4.

Fig. 5.

FIG. 1 is a perspective view of a golf putter showing my new design;

FIG. 2 is a front elevational view of the putter head;

FIG. 3 is a top plan view of the putter head;

FIG. 4 is a front edge view of the putter head;

FIG. 5 is a rear edge view of the putter head; and

FIG. 6 is a rear elevational view of the putter head.

I claim:

The ornamental design for a golf putter, as shown and described.
